PULP HYDRATOR

Harold Donald Wells, Glens Falls, N. Y.

Application January 17, 1933, Serial No. 652,216

5 Claims. (Cl. 92—20)

The invention aims to provide a new and improved hydrator for paper stock or pulp, by means of which a greatly increased production may be effected, at the same time producing such perfectly treated and gelatinized pulp as to permit the production of stronger and better paper.

In carrying out the above end, intermeshed gear teeth are provided on relatively rotatable members, and the pulp is passed between these members, so that the teeth create high pressure as they mesh, and as they unmash create suction or vacuum to some extent. The rolling and pressing of the fibre bundles in the pulp tend to separate them into single fibres and moreover the suction or vacuum tends further to produce this result, as well as opening up any of the tube-like fibres to receive the water of hydration. The complete action on the fibres of rolling, vacuum and pressure, gelatinizes them so that stronger and better paper may be produced, and greatly increases the production and efficiency of the hydrator.

The present invention is an improvement upon the pulp and paper stock hydrator of my Patent 1,897,157 dated February 14, 1933 and aims to make said hydrator more efficient in operating on certain stock which tends to slide ahead of the pinch of the rolling or pressing surfaces in the machine of said patent. In the present invention, the provision of intermeshing teeth on said rolling or pressing members insures that such stock will be acted upon and more effectively treated to produce the desired hydration.

The invention is illustrated in the accompanying drawings and is hereinafter fully described and claimed.

Fig. 1 is a vertical longitudinal sectional view showing one form of the hydrator.

Fig. 2 is an enlarged fragmentary transverse sectional view on line 2—2 of Fig. 1.

Fig. 3 is a longitudinal sectional view showing a modified form of construction.

Fig. 4 is a transverse sectional view on line 4—4 of Fig. 3.

Fig. 5 is a longitudinal sectional view showing a still further form of construction.

Fig. 6 is a detail transverse sectional view on line 6—6 of Fig. 5.

Preferred forms of construction have been shown and will be specifically described, with the understanding however, that within the scope of the invention as claimed, variations may be made.

In Figs. 1 and 2, the numeral 10 denotes an elongated cylindrical casing having a pulp inlet

opening 11 communicating with a pulp conducting elbow 12, said casing also having a pulp outlet 13. A shaft 14 passes longitudinally through the casing 10 along the axis of the latter, is mounted in appropriate bearings 15 and extends through stuffing boxes 16, said shaft having a pulley 17 by means of which it may be driven. An impeller 18 is keyed on the shaft 14 near the inlet opening 11 and operates within the channel of a channeled ring 19 which is secured in the 10 casing 10, at one end of the latter. Between the impeller 18 and the opposite end of the casing, I provide a plurality of sun gears 20 which are keyed to and secured upon the shaft in any desired way. Floating planet gears 21 mesh with 15 the sun gears 20 and with annular orbit gears 22 which are secured in the casing in contact with the side wall of the latter. Preferably, each sun gear 20 is surrounded by a plurality of the planet gears 21, eight planet gears being 20 preferably although not necessarily provided in each plurality.

All of the gears 20, 21 and 22 are provided with pulp rolling faces 23, said pulp rolling faces being of continuous form and being substantially 25 of the same diameter as the pitch lines of the gears, respectively. The pulp is acted upon by these rolling surfaces 23 and by the intermeshing teeth of the gears, with the result that effective hydration is carried out. The pulp is forced to 30 take a zig-zag course through the hydrator, due to the provision of outer and inner annular baffles which are disposed in staggered relation. The baffles 24 are clamped between the orbit gears 22 and extend into spaced relation with the sun 35 gears 20, whereas the baffles 25 are clamped between certain of said sun gears and project radially into spaced relation with said orbit gears 22. The last baffle 25 at the discharge end of the machine may well engage a spacing ring 26 which 40 abuts one end wall 27 of said casing, so that the parts 19, 22, 24 and 26 may be tightly held between said end wall 27 and the opposite end wall 28 of the casing. The impeller 18, the sun gears 20 and the baffles 25 may all be keyed upon the 45 shaft 14 and the sun gear at the discharge end of the machine may well abut a collar 29 on said shaft.

When shaft 14 is driven and pulp is admitted through the elbow 12 and opening 11, the impeller 50 18 assists in feeding this pulp through the machine, and the baffles 24 and 25 cause said pulp to take a zig-zag course. During its travel, it is successively acted upon by the intermeshing teeth and the rolling surfaces of the numerous gears 55

and said teeth and surfaces produce the effects upon the pulp, hereinbefore set forth. It will be observed on reference to Fig. 2 that the pulp rolling surfaces 23 formed by the cylindrical enlargements or rollers at the ends of the planetary gears 21 form bearing members for the gears; and that such enlargements at least partially overlie the sides of the teeth of said planetary gears to form pockets in which the stock is successively entrapped and extruded therefrom by the action of the entering teeth.

In Figs. 3 and 4, the teeth of the sun gears 20^a, planet gears 21^a and orbit gears 22^a, extend throughout the widths of these gears. These teeth as well as any of the others herein disclosed, may be of any desired type such as conventional spur type, helical, herringbone, staggered, etc. Between certain of the sun gears 20^a, inner baffles 25^a are positioned, said baffles being free to rotate upon the shaft 14^a. These baffles project radially beyond the sun gears 20^a and terminate in spaced relation with the orbit gears 22^a. Other annular baffles 24^a are interposed between the baffles 25^a and have their outer peripheral edges 25 in close proximity to the planet gears 22^a. The inner peripheral edges of these baffles 24^a are spaced radially from the sun gears 20^a and are provided with spiders 30 which are free to rotate upon the shaft 14^a, between some of said sun gears. Longitudinal shafts 31 pass through the baffles 24^a and 25^a and through the planet gears 21^a, and the ends of said shafts may be upset as shown at 32, to hold them in place.

In securing the orbit gears 22^a within the casing 10^a, I may well make use of spaced rings 33, and between the casing end wall 27^a and the adjacent gear 22^a, a ring 26^a may be used.

In Figs. 5 and 6, most features of construction are the same as in Figs. 1 and 2, but changes are made in the sun gears 20^b, the planet gears 21^b, and the orbit gears 22^b. The teeth 34 of the planet gears 21^b, are preferably about semi-cylindrical as shown, and the portions of the gear peripheries between said teeth, are concentric with the axes of the gears 21^b, providing pulp rolling surfaces 35. The sun gears 20^b and orbit gears 22^b, are formed with grooves 36 between their teeth 37, shaped to engage the teeth 34 of the planet gears 21^b, and the ends 38 of said teeth 50 co-operate with the surfaces 35 of said planet gears, to effectively roll and press the pulp. Similar actions are also performed by the co-acting faces of the teeth 34 and grooves 36.

It will be understood that in each of the three embodiments illustrated in the drawings, any number of the sets of transversely arranged planetary gearing may be used. It will also be observed that in the form shown in Figs. 1 and 2, the rolling or bearing surfaces 23 maintain the gears in fixed center-to-center relation and properly spaced and meshed, that function being performed in the construction shown in Figs. 3 and 4 by the use of a cage composed of the spiders 30 and the bearing shafts 31, and in the form shown in Figs. 5 and 6 by the rolling or bearing surfaces 35 and 38.

I claim:—

1. A pulp hydrator comprising an elongated casing having an inlet and an outlet, a driven shaft mounted longitudinally in said casing and disposed co-axially therewith, a plurality of sun gears secured on said shaft, planet gears meshing with said sun gears, orbit gears secured at the casing side wall and meshing with said planet gears, annular baffles projecting radially beyond said sun gears and terminating in spaced relation with said orbit gears, and additional annular baffles between the first named baffles and co-operable therewith in causing the pulp to zig-zag through the hydrator.

2. A pulp hydrator comprising an elongated casing having an inlet and an outlet, a driven shaft mounted longitudinally in said casing and disposed co-axially therewith, a plurality of sun gears secured on said shaft, planet gears meshing with said sun gears, orbit gears secured at the casing side wall and meshing with said planet gears, and outer and inner sets of annular baffles for causing the pulp to zig-zag through the hydrator, said outer baffles being clamped between said orbit gears, said inner baffles being clamped between said sun gears.

3. A pulp hydrator comprising an elongated casing having an inlet and an outlet, a driven shaft mounted longitudinally in said casing and disposed co-axially therewith, a plurality of sun gears secured on said shaft, planet gears meshing with said sun gears, orbit gears secured at the casing side wall and meshing with said planet gears, annular baffles rotatable upon said shaft between certain of said sun gears and projecting radially beyond the latter in spaced relation with said orbit gears, additional annular baffles between the aforesaid baffles and having their outer peripheral edges in close proximity to said orbit gears, the inner peripheral edges of said additional baffles being radially spaced from said sun gears and being provided with spiders rotatable on said shaft between certain of said sun gears, and longitudinal shafts passing through all of said baffles and said planet gears.

4. A pulp hydrator having relatively rotatable members between which the pulp is fed, said members having intermeshed gear teeth and having co-acting continuous cylindrical pulp rolling surfaces at the ends of their gear teeth, to act upon the pulp, and baffles to cause a zig-zag flow of the pulp through the hydrator, the diameters of said pulp rolling surfaces being substantially the same as the pitch lines of said gear teeth.

5. A pulp hydrator having impelling means, relatively rotatable members between which said impelling means feeds the pulp, said members having intermeshed gear teeth and having co-acting continuous cylindrical pulp rolling surfaces at the ends of their gear teeth, to act upon the pulp, and baffles to cause a zig-zag flow of the pulp through the hydrator, the diameters of said pulp rolling surfaces being substantially the same as the pitch lines of said gear teeth.

HAROLD DONALD WELLS.
